UNITED STATES PATENT OFFICE.

WILLIAM H. CURTIN, OF BROOKLYN, NEW YORK.

VALVE.

967,050.

Specification of Letters Patent. Patented Mar. 14, 1911.

Application filed May 24, 1910. Serial No. 563,225.

To all whom it may concern:

Be it known that I, WILLIAM H. CURTIN, a citizen of the United States of America, and residing at Brooklyn, in the county of Kings 5 and State of New York, have invented certain new and useful Improvements in Valves, of which the following is a specification, such as will enable those skilled in the art to which it appertains to make and use 10 the same.

This invention relates to valves, particularly to steam valves, which require packing to prevent leakage, and the object thereof is to provide self-contained means in such a 15 valve which permit the substitution of packing without shutting off the steam; a further object is to provide such non-leaking means at a plurality of points whereby the stoppage is correspondingly multiplied; and a still 20 further object is to provide such means which are simple in construction and use, which do not require any radical change in the valve construction, and which are very inexpensive.

25 My invention is fully described in the following specification, of which the accompanying drawing forms a part, said drawing being a central vertical section taken through a valve of the angle type.

30 In the said drawing I have shown the casing *a* of a valve provided with the usual inlet port *a*² adapted for connection with the steam system, and an outlet port *a*³ adapted to be connected with a radiator or the like 35 by means of a connection *a*⁴ and coupling *a*⁵, and said casing being also provided with a removable top *b* having a screw-thread *b*² therein and having also a removable cap *b*³ within which the usual packing *b*⁴ is placed, 40 all of said parts being of the usual or any desired construction.

Rotatably mounted in the top *b* is a valve stem *c* provided with the usual handle *c*² and screw-thread *c*³ in engagement with the 45 thread *b*² whereby the stem is raised or lowered and said stem carries, in the form shown, a disk-valve *c*⁴ seated at *c*⁵ to close the inlet port *a*², these parts being also of the usual or any desired form. It will be ob- 50 served that the upper part of the stem is of considerably less diameter than that portion bearing the screw-thread, forming a shoulder therebetween, and this shoulder, as shown at *d* I give an inclined, tapered, or similar form 55 and adapted to closely engage the similarly formed top *d*² of the screw-threaded recess of

the top *b*, in order to prevent any passage of steam or other similar fluid therebetween and, as stated, I may make the contact surfaces *d* and *d*² of any suitable conformation 60 in order to insure this result. Intermediate of the shoulder *d* and the disk *c*⁴ I provide a flange *d*³ of considerably greater diameter than this part of the stem *c*, said flange being inclined, tapered, curved, or otherwise 65 formed upon its upper surface as shown at *d*⁴ and, as shown at *d*⁵, I recess the lower end of the removable top *b* of a size and shape corresponding to the surface *d*⁴ in order to prevent leakage therebetween when the surfaces *d*⁴ and *d*⁵ are in close contact and, in practice, I make the distance between the surfaces *d* and *d*⁴ of the stem the same as that between the surfaces *d*² and *d*⁵ of the removable top *b* in order that the contact 70 of the corresponding surfaces will occur simultaneously and thus double the efficiency of my device; and, if desired, I may provide such contacting surfaces at other points, although not shown in the drawing, it being 75 believed that contact at two points will suffice for ordinary conditions. It will therefore be seen that the valve-stem may be in its uppermost position, leaving the valve fully open, and still prevent fluid from escaping 80 through the passage provided for the said stem, thus permitting the removal of the cap *b*² for the removal and substitution of the packing *b*⁴, this not being possible with valves of this type as at present constructed, 85 and in the use of which it is necessary to shut off the fluid from an entire system or from that portion in which re-packing is to be done.

As hereinbefore stated, I do not limit myself to any specific type of valve wherein my improvement might be employed, neither to the particular fluid passing therethrough, nor to the exact configuration of the contacting surfaces, my invention being in the provision of non-leaking means between a valve-stem and casing with the valve in full 100 open position and during the substitution of the usual packing.

Having fully described my invention, 105 what I claim as new and desire to secure by Letters Patent, is:—

1. A valve casing having a valve therein and provided with an interior screw thread, inwardly inclined at one end and outwardly 110 flared at the other end, and a stem connected with said valve and provided with a screw

- thread engaged by said first named thread, said valve stem being inwardly inclined at one end of said screw thread and being provided with an outwardly flared flange at the 5 other end of said thread, said inclined and flared portions of said valve stem being adapted to be seated in the inclined and flared portions respectively of said valve casing, simultaneously.
- 10 2. In a valve casing, a valve, and a stem connected to the valve, said stem being provided with a screw thread for a portion of its length and being inwardly inclined at the

outer end of said thread and being provided with an outwardly flared flange at the inner 15 end of said thread, said valve casing having coöperating seats for the inclined and flared portions of said stem.

In testimony that I claim the foregoing as my invention I have signed my name in presence of the subscribing witnesses this 18th 20 day of May 1910.

WILLIAM H. CURTIN.
